UNITED STATES PATENT OFFICE.

DANIEL W. DAVIDSON, OF BIG SPRING, TEXAS.

SASH-PULLEY MARKER.

Application filed March 2, 1925. Serial No. 12,650.

This invention relates to improvements in marking devices particularly intended for use in connection with window frames.

An important object of the invention is
5 to provide a marking device of this character whereby the center points for drilling in forming sash pulley slots may be quickly and accurately made.

A further object of the invention is the provision of a device of this character whereby these centerpoints may be uniformly marked in any desirable number of window frames.

A still further object of the invention is to provide a marker of this character which is extremely simple in construction, durable and efficient for the purpose intended.

Other objects and advantages of this invention will be apparent during the course 20 of the following description.

In the accompanying drawing forming a part of this specification and in which like numerals will be used to designate corresponding parts throughout the same:

25 Figure 1 is a partial side elevation of a window frame showing my improved device associated therewith,

Figure 2 is a side elevation of the device embodying my invention, and
30 Figure 3 is a horizontal sectional view taken on the line 3-3 of Figure 1.

In the drawing wherein for the purpose of illustration is shown the preferred embodiment of my invention, the numeral 5 generally indicates one of the side rails of a window frame provided in the central portion thereof with a longitudinal groove (for the purpose of receiving therein the usual parting strip, (not shown)). At the upper extremity of the side rails 5 is shown the usual head rail 7.

The description thus far has dealt with a simple form of window frame shown merely to illustrate the application of my device in connection therewith.

Referring now more particularly to the construction embodying my invention, the numeral 8 designates a longitudinal guide strip of preferably metallic construction and 50 rectangular in cross section. This strip is adapted to engage the parting strip groove 6 and adapted to be slidably mounted therein. The lower portion of the strip 8 is provided with a plurality of screw threaded 55 openings 9 adapted to receive therein a suitable retaining screw 10.

Carried by the outer edge of the longitudinal guide strip 8 is a centering plate 11 substantially rectangular in formation and provided with a longitudinal groove formed in the central portion of the rear face thereof, this groove being adapted to engage the outer projection of the guide strip 8 in order to retain the centering plate securely in position. The front side of the centering plate is provided with a countersunk opening 12 adapted to receive therein the retaining screw 10 which securely retains the plate in position upon the guide strip 8. A plurality of centering screws 13 are mounted in vertical alignment adjacent the vertical sides of the centering plate, these screws being mounted in suitable screw threaded openings and provided on the inner extremities with centering points 14.

In use, my improved device is adapted to provide means for rapidly and accurately impressing the center points for drilling the side rails of window frames in forming the pulley slot. It is customary in forming the slot in the sash frame to bore a plurality of aligned holes through the rail and chip the intervening material to form a rectangular opening through which the sash weights are inserted and into which the pulleys are mounted. It is necessary in performing this operation to accurately center the drilling openings which is now usually done by measurement from the head rail. This consumes a substantial amount of time and labor and often results in inaccurate work.

With my improved device the centering of these drilling holes is accomplished in a fraction of the time usually consumed and insures accurate workmanship. The distance of the pulley slots from the head rail is first ascertained and the centering plate 11 is secured in suitable relation upon the guide strip 8. This is accomplished by operation of the retaining screw 10 and corresponding movement of the centering plate, the lower portion of the guide strip being provided with a plurality of screw threaded openings to permit the adjustment. When the centering plate has been secured in its proper position upon the guide strip the connected device is placed in association with the window frame side rail, the guide strip engaging the parting strip groove formed therein. The guide strip is then forced upwardly against the head rail and the centering plate forcibly struck with a hammer or

any suitable implement. This impact will cause the centering screws to mark the proper centering points in the frame and the centering operation is completed.

It is to be understood that the form of my invention herewith shown and described is to be taken as the preferred example of the same, and that various changes as to the shape, size and arrangement of parts may be resorted to without departing from the spirit of the invention or the scope of the subjoined claims.

Having thus described my invention, I claim:

1. A window sash marker including a guide strip having a plurality of openings therein, a plate having an opening mounted on the guide strip, a retaining member engageable with the openings formed in the plate and guide strip for adjustable connection thereof, and marking members carried by the plate.

2. A device of the character described including a guide strip, a longitudinally adjustable plate secured upon the guide strip, means for adjustably securing the plate upon the guide strip, and a plurality of marking members threadedly mounted on the side edges of the plate for independent adjustment.

3. A marking device including a guide strip having a plurality of threaded openings, a plate formed with a central opening mounted on the guide strip, a retaining member adapted for threaded engagement with the openings in the guide strips adapted to adjustably secure the plate on the guide strip, and a plurality of tapered marking members mounted in the sides of the plate, arranged for transverse movement through the plate for independent adjustment.

In testimony whereof I affix my signature.

DANIEL W. DAVIDSON.
